UNITED STATES PATENT OFFICE.

JACOB STIBIUS, OF NEW YORK, N. Y., ASSIGNOR TO THE LARVEK CORPORATION, OF BROOKLYN, NEW YORK, A CORPORATION OF NEW YORK.

BOTTLE CAP OR CLOSURE.

Application filed November 23, 1928. Serial No. 150,721.

This invention relates to closures generally, but is more particularly adapted for employment as a cap for bottles provided with integrally formed radially extending lugs circumferentially spaced about the necks thereof.

The cap or closure of the present invention is primarily a sheet metal cap. Sheet metal caps have long been used for closing bottles, jars, etc., and have been constructed in various ways. For example, it is common practice to emboss threads on the skirt of the cap and provide a helical thread on the bottle neck. Furthermore caps have been made with embossed bayonet joints in the skirts thereof and which embossed joints are adapted to cooperate with lugs on the bottle neck. Caps of this character have, however, not met with favor for the reason that it is practically impossible to thus shape the parts for proper repetitive cooperation with the lugs.

The most common form of cap now in use, is that wherein the free edge of the skirt is provided with inwardly turned flanges adapted to cooperate with threads or lugs formed on the bottle. This last mentioned type of cap is economical to manufacture, but experience has shown that a cap adapted for repetitive use cannot be satisfactorily produced by inturning flanges from the free edge of a cap skirt. The metal employed in the cap must necessarily be light and when the cap is used the lugs become bent and will not produce a tight seal.

The primary object of the present invention is to provide a simple, efficient and economical cap or closure for jars, bottles and the like, which is susceptible to long repetitive use for the production of tight seals without distortion of the cap.

In practically carrying out the invention, the cap is struck up from sheet metal and is provided with a skirt, the free edge of which is returned upon itself and preferably rolled to form a finished edge and at the same time produce a reinforcing flange. The main body of the skirt above the flange is formed into integral alternate segments of different diameters. That is to say, every other segmental portion of the skirt is of one diameter, sufficiently large to fit over the lugs of a bottle neck, while every other intermediate segmental portion of the skirt is of a smaller diameter sufficiently large to

closely embrace the neck of said bottle immediately below the lugs. Each of the smaller segmental portions of the skirt is provided with a circumferentially disposed opening which is punched out from the wall 60 of the skirt and said openings are of such length that both ends of the openings preferably extend into the next adjacent segmental portions of the larger diameter. This is the preferred construction although, 65 if desired, only one end of each opening may be extended as described.

The successive segmental portions of the skirt circumferentially form a continuation of one another, being joined together by easy, 70 sweeping curves and the extended ends of the several openings extend into these curved portions to a point in each radially distant from the center of the cap, slightly less than the overall radial dimension of the lugs. 75 Such a cap may be placed on the neck of the bottle by lowering the cap over the mouth of the neck with the larger segmental portions of the skirt juxtaposed with the lugs on the bottle neck, so that when the cap comes to 80 rest on top of the bottle, the lugs will be housed within the larger segmental portions of the cap. The openings in the smaller segmental portions are positioned at substantially the same elevation as the lugs occupy 85 when the cap is thus placed, and to lock the cap on the bottle said cap must be rotated to bring the lugs into said openings. However, in order to thus position the parts, it is necessary to pass each lug through that 90 end of the adjacent opening which is of a less distance from the axis of the bottle than the overall radius of the lug and this can only be accomplished by applying sufficient force to flex the skirt at the end of the openings to permit the lugs to slip by. 95

In practice, this does not require the expenditure of a great amount of force, but it requires sufficient to be readily perceptible, and, furthermore, after the lugs have been 100 sprung through these constricted portions, they will maintain their positions in the slots and will not become released through inadvertent rotation of the parts, since said parts will be in effect locked together. This will be apparent from the fact that after the lugs have passed by the constrictions, the ends of the slots will spring back to their normal form and lock the parts against 105 retrograde movement. 110

The foregoing manner of associating a cap with the lugs of the bottle neck constitutes the basis of this invention and provides for a locked construction of simple, durable and repetitive character embodying no separate movable parts and susceptible of economical manufacture.

Features of the invention, other than those adverted to, will be apparent from the hereinafter detailed description and claims, when read in conjunction with the accompanying drawings.

The accompanying drawings illustrate one practical embodiment of the invention, but the construction therein shown is to be understood as illustrative, only, and not as defining the limits of the invention.

Figure 1 is a top plan view of a cap embodying the present invention.

Figure 2 is a side elevation showing the same secured to a bottle neck.

Figure 3 is an underneath plan view of the cap removed from the bottle.

Figure 4 is a section on the line 4—4 of Figure 1.

Figures 5 and 6 are sections on the line 6—6 of Figure 2. The former of these views shows the cap loosely positioned on the bottle, while the latter shows the cap turned into tight sealing position on said neck.

Figure 7 is an enlarged fragmental section of a portion of the cap and one of the lugs of a bottle showing, graphically, the manner in which the cap is flexed to permit the lugs to move into and out of the lug receiving slots of the cap skirt.

The cap or closure of the present invention is adapted for use on bottles, jars or similar containers, but, for the purpose of illustration, I have shown the invention as a bottle cap. In the drawings, 1 designates a cap generally. It is stamped up from sheet metal to form a shell, which, in the form of Figures 1 to 6 embodies a closed flat top and a depending skirt having an open bottom. The bottom edge of the skirt is circular and is returned or rolled upon itself, as shown at 2, to form a reinforcing flange or ring and to provide a finished edge. That portion of the skirt above the ring 2 is formed on two distinct diameters. That is to say, the segmental portions 3 are of greater diameter than the intermediate segmental portions 4. In other words, the portions 4 may be referred to as re-entrant portions.

5 designates the neck of a bottle with which the cap is adapted to cooperate. This neck is provided near its top with a plurality of radially extending lugs 6, which, in practice, are preferably so constructed that their under side abutments 7 will be substantially flat, as best shown in Figure 4. These abutments, in order to properly draw from the mold, generally have a slight in-

clination and where they join the neck of the bottle there must be a slight fillet, but, for the best results, the said fillet should be as small as possible and the abutment faces 7 should be as flat as possible. Three lugs 6 are shown on the neck of the bottle, and, accordingly, the cap is provided with a corresponding number of the larger segments 3 and a like number of the interposed smaller segments 4. The interior radius of the cap at the larger segments is equal to or slightly greater than the radius of the neck of the bottle at and including the projecting lugs 6, while the interior radius of the smaller segments 4 is equal to or slightly greater than the radius of the neck of the bottle directly below the abutments 7.

The skirt of the cap is formed, so that it will be circumferentially continuous. That is to say, the skirt is formed so that the larger and smaller sections join one another in smooth and even curves, as shown best in Figures 5 and 6.

In order to cooperate with the lugs 6, each of the reentrant portions is provided with a circumferential slot, at least one end of which extends into one of the larger contiguous segments 3. The extension at one end of the slot is sufficient, within the present invention, but, in practice, I preferably extend both ends of each slot into the two contiguous segments 4 of the larger diameter, as clearly shown in Figures 2 and 5. These extensions of the slots are designated 8^a. The degree to which the portions 8^a of the slots 8 extend into the larger segmental portions of the skirt, is of primary importance in this invention, as is graphically shown in Figure 7.

In this figure, the radius of the interior of the larger segmental portions 3 is designated R₁. The outer or overall diameter of the lugs of the neck is designated R₂ and the portions 8^a of the slots 8 which extend into the portions 3 terminate at a radius R₃. In other words, the termini 8^b of the slot extensions 8^a are normally spaced from the axis of the cap a distance equal to R₃. As is apparent from Figure 7, the radius R₃ is slightly less than the radius R₂, while the radius R₁ is slightly greater than the radius R₃. The difference between the latter two radii is to permit of slight clearance, while the difference between the former two radii is to preclude the free passage of the lugs apast the termini 8^b. The sheet metal from which the cap is manufactured, however, possesses sufficient inherent resiliency to permit of a flexing or springing of the terminal abutments 8^b when they are subjected to outward radial pressure, without, however, permanently deforming the cap at these points.

When the cap is lowered over the bottle neck, the lugs will be housed within the

larger segmental portions 3 and each lug will occupy a position within the respective larger segmental portion of the cap, as shown in full lines in Figure 7. In order 5 to secure the cap to the bottle, the cap should be rotated in a clockwise direction in Figure 7, and when this is done, the rounded end of each lug will bear against the cap skirt in the immediate proximity of 10 the abutment 8^a and will cause such abutment to be sprung outwardly from its normal full line position of Figure 7 to the dotted line position of such figure, to permit the lug 6 to pass by said abutment and 15 enter the slot 8. As rotation of the cap is continued, said cap is moved to bring each lug 6 wholly within the corresponding slot 8 and as each abutment 8^b passes the rear 20 end of the corresponding lug, such abutment will return to its normal unflexed position and the parts will appear, as shown in Figure 6.

When the cap is positioned with all of the 25 lugs wholly within the respective segments of smaller diameter, the cap will be locked in place against inadvertent rotation for the reason that in order to remove the cap, the abutments must be sprung as described and the force required to do this must be 30 positively supplied.

It should be noted that in practice the difference between the radii R_2 and R_3 is 35 relatively small. A marked difference is not essential to produce the locking engagement referred to and if the distance is too great, the abutment 8^b will be stressed beyond its elastic limit and will become permanently 40 distorted. For the best results, there should be no permanent distortion of the cap if a truly repetitive cap is to result.

In order that the tightest possible seal may 45 result when the cap is turned into sealing position as described, the lower edge 9 of each slot 8 is preferably slightly arched, as shown in Figure 2, so as to be highest in the center, although this feature may be modified without departing from the invention. If 50 the surface 9 is made perfectly flat, a satisfactory seal will result for the reason that the springing of the cap as described will cause the cap to be pulled down tightly over the mouth of the bottle.

A careful analysis of the mode of operation 55 of the cap in forming the seal shows that it embodies a high degree of mechanical efficiency. For example, it will be apparent from Figures 4 and 5, that those parts 4^a of the re-entrant portions directly below the 60 slots will closely hug the neck of the bottle, so that the edges 9 engage with the lug abutments 7 at the base of the lugs. There 65 will thus be relatively little tendency of the cap to flex radially outward to disengage the lower edges of the slots from these lugs.

Furthermore, the lower edges 9 of the slots are substantially flat in a radial direction and this fact, of itself, minimizes the tendency of outward radial slippage with respect to the lugs. These flat clamping surfaces are almost impossible to obtain by embossing or bending operations, such as have been common under the prior practice in the formation of embossed bayonet slots or bent 70 in flanges. Inasmuch as the sealing stresses 75 are applied to the lugs directly adjacent the neck of the bottle, there will be little possibility of breaking off the lugs as there is practically no leverage at this point of engagement. 80

The portions 4^a of the skirt and reinforcing flange or ring 2 cooperate to impart strength to the free edge of the skirt, and, as will be apparent from Figure 4, fully reinforce the inclined edges 9 of the slots. 85 These edges may be slightly stressed in a downward direction, as the cap is forced into sealing position, so that the parts of the reentrant portions which carry these inclined edges will be under tension, when the cap is in sealing position, but the reinforcing ring and flange will impart such strength to these parts as to preclude their permanent deformation. 90

The novel contour of the body of the cap forms a convenient grip which permits the cap to be readily grasped and rotated into the desired position. 95

It will be apparent from the foregoing 100 detailed description that in accordance with the present invention the segmental portions 3 of the skirt of the shell constitute passages extending longitudinally of the skirt and into which lugs are adapted to be received during the placing of the closure on the receptacle. From these longitudinal passages, the circumferentially disposed slots extend, the inlet ends of which slots are formed to present a radial constriction to the lugs as the closure is rotated to bring it into 105 sealing position. This radial constriction constitutes a lock which effectually precludes the inadvertent release of the closure from the lugs. The closure is such as to function 110 efficiently, may be economically manufactured and may be used repetitively for indefinite periods without distortion. 115

The accompanying drawings show the invention in its preferred practical form, but 120 the invention is to be understood as fully commensurate with the appended claims.

Having thus fully described the invention, what I claim as new and desire to secure by Letters Patent is:

1. A closure embodying a metal shell formed with a skirt, segmental portions of which are alternately of different diameters, the larger of which is sufficiently great to embrace the lugs of a cooperating receptacle 125

and the smaller of which is of a size to closely fit the receptacle directly beneath the lugs, and the segmental portions of the smaller diameter being provided in spaced relation to the lower edge of the skirt with circumferentially disposed slots at least one end of each of which extends into an adjacent segmental portion of the larger diameter and terminates in a yielding abutment normally spaced from the axis of the closure, a distance less than the overall radius of said lugs, whereby it is necessary to flex said abutments to pass the lugs from the larger to the smaller segmental portions of the skirt and vice versa.

2. A closure embodying a metal shell, the free edge of which is provided with a reinforcing flange, segmental portions of the side wall of the shell being alternately of different diameters, the larger of which is sufficiently great to embrace the lugs of a cooperating receptacle and the smaller of which is of a size to closely fit the receptacle directly beneath the lugs, and the segmental portions of the smaller diameter being provided in spaced relation to the lower edge of the skirt with circumferentially disposed slots at least one end of each of which extends into an adjacent segmental portion of the larger diameter and terminates in a yielding abutment normally spaced from the axis of the closure a distance less than the overall radius of said lugs, whereby it is necessary to flex said abutments to pass the lugs from the larger to the smaller segmental portions of the skirt and vice versa.

3. A closure embodying a metal shell, the free edge of which is circular and is returned upon itself to provide a reinforcing ring, segmental portions of the side wall of the shell above the ring being alternately of different diameters, the larger of which is sufficiently great to embrace the lugs of a cooperating receptacle and the smaller of which is of a size to closely fit the receptacle directly beneath the lugs, and the segmental portions of the smaller diameter being provided in spaced relation to the lower edge of the skirt with circumferentially disposed slots at least one end of each of which extends into an adjacent segmental portion of the larger diameter and terminates in a yielding abutment normally spaced from the

axis of the closure, a distance less than the overall radius of said lugs, whereby it is necessary to flex said abutments to pass the lugs from the larger to the smaller segmental portions of the skirt and vice versa.

4. A closure embodying a metal shell having a skirt portion provided with a plurality of circumferentially disposed openings adapted to receive lugs of a cooperating receptacle, the entrance of each of said openings being of less radius than the overall radius of the receptacle lugs, whereby the skirt is radially stressed when the lugs enter and leave said openings.

5. A closure embodying a metal shell formed with a skirt having means defining passages into which the lugs of the receptacle may be moved by relative axial movement between the closure and the receptacle and also provided with passages extending circumferentially of the closure and leading from the first mentioned passages, the inlet end of each circumferential passage being formed with a radially yieldable constriction adapted to be stressed radially solely outwardly by the movement of said lugs into and out of said circumferential passages.

6. A closure embodying a sheet metal shell having a skirt provided with circumferentially extending slots, the major portions of the lengths of which are spaced a uniform distance from the axis of the skirt and at least one end portion of each slot terminating in an abutment spaced from the axis of the cap a distance less than the overall radius of the lugs of a receptacle with which the closure is adapted to cooperate, said abutments being radially yieldable to permit the lugs of the receptacle to enter and leave the slots.

7. A closure embodying a sheet metal shell provided with circumferentially disposed passages adapted to be engaged and disengaged with lugs on a receptacle by relative rotation between the shell and receptacle, the inlet ends of said passages being radially constricted to necessitate radial stressing of the shell during the engagement and disengagement of the passages with the lugs.

In testimony whereof I have signed the foregoing specification.

JACOB STIRISS.
